DESIGN

A. DWIGHT.

TYPE CASE.

Patented Aug. 31, 1886.

D16,881.

UNITED STATES PATENT OFFICE.

ALFRED DWIGHT, OF AGAWAM, MASSACHUSETTS.

DESIGN FOR A TYPE-CASE.

SPECIFICATION forming part of Design No. 16,881, dated August 31, 1886.

Application filed July 24, 1886. Serial No. 209,029. Term of patent 3½ years.

To all whom it may concern:

Be it known that I, ALFRED DWIGHT, a citizen of the United States, residing at Agawam, in the county of Hampden and Commonwealth 5 of Massachusetts, have invented and produced a new and original Design for a Type-Case, of which the following is a specification, reference being had to the accompanying photographic illustration, forming part thereof.

- 10 In the photograph, *a* indicates the frame of my type-case, the same being divided by a central partition, *e*, into two rectangular compartments. Within each of these compartments is arranged a series of cells, *c*. Heretofore, so far as I am aware, these cells have 15 been rectangular as to their interior surface, or have been saucer-shaped—that is to say, they have been composed of four vertical sides and a flat bottom, or have had four sides with a 20 bottom formed on a regular curve from each of said sides, the curves meeting at the center of the cell, thus forming a saucer-shaped compartment. I am also aware that in one instance the saucer-shaped grooves mentioned 25 have been intersected by a series of vertical partitions, thus forming a series of compartments having vertical sides and a saucer-shaped bottom extending from front to rear. My new design differs from either of these 30 forms, in that the individual cell is composed of a bottom having the contour of a bisected ellipse extending from the front to the rear of the cell, and two vertical sides also extending from front to rear thereof.
- 35 As will be seen by reference to the photograph, my type-case is composed of the frame *a*, divided by the partition *e* into two compartments. Within each compartment is a series of parallel ridges, *b*, extending longitudinally of the frame, the apex of each ridge being substantially flush with the upper surface of the frame. Each ridge is joined to the adjacent ridge throughout its entire length by a curve having the contour of an ellipse bisected on its greatest diameter. This con- 40 formation results in a series of parallel depressions, *c*, between the ridges, extending longi- 45

tudinally of the frame, the contour of the depressions being that which would remain if a series of semi-elliptical moldings were removed 50 from the body of the material of which the cells are constructed. At intervals these ridges and depressions are intersected at a right angle by a series of thin partitions, *d*, extending from front to rear of the frame. These partitions are substantially flush with the upper surface of the frame, and of the same depth as the frame, so that, with the ridges and depressions above described, they form a series of cells having two vertical sides and a bottom 55 which curves from front to rear of the cell in the contour of a bisected ellipse.

The complete design thus formed differs materially from either of those above noted as being well known in the art.

60 The leading feature of my design consists of the type-case made up of a frame having a series of longitudinal and alternating ridges and depressions and a series of transverse partitions, the contour of the depressions being that 65 of a bisected ellipse.

I claim—

1. The design for a type-case herein shown and described, the same consisting of a rectangular frame divided transversely into two 70 equal compartments, a series of alternating ridges and depressions extending longitudinally of the frame, the contour of the depressions being that of an ellipse bisected on its greatest diameter, and a series of vertical partitions extending transversely of said frame 75 and intersecting said ridges and depressions at a right angle.

2. In a design for a type-case, a rectangular frame divided into two compartments, each 80 compartment containing a series of cells having two vertical sides and a bottom extending from front to rear upon the curve of a semi-ellipse.

ALFRED DWIGHT.
